ATTACHMENT FOR OVERSIZE FORMS

George A. Rutkoskie and Nelson S. Welk, Athens,
Ohio, assignors to The McBee Company, Athens, Ohio, a corporation of Ohio

Application July 26, 1935, Serial No. 33,199

6 Claims. (Cl. 101—353)

Our invention relates to presses of the type shown in Reissue Patent No. 19,642, issued July 9, 1935, and more particularly to provide improved means to convey the wax carbon compound to an oversize form. That patent describes means to adapt a flat bed printing press to wax carbon printing. On such presses the size of the form to be wax carboned is usually limited due to the construction of the press. Some manufacturers of this type of press furnish auxiliary ink distributor rolls which can be attached to the frame at a point in front of the impression cylinder. These auxiliary rollers receive ink from type or plates which are located sufficiently rearward to pass under the regular inking rollers and in turn distribute it to other type or plates located at the extreme front of the type bed. In these attachments the contacting rollers are rotated by the cohesion or tack of the printer's ink. However, as explained in the said Reissue Patent No. 19,642, issued July 9, 1935, melted wax carbon does not possess sufficient tack to cause the rollers to drive the contacting ones. Moreover in a wax carbon press the rollers must be heated.

Our invention has for its principal object to provide means to positively drive the rollers in the attachment.

A further object is to provide improved means to heat the vibrator roller of the attachment.

A further object is to provide an improved form of brush contact for conducting the electric current to the heating elements contained in said roll.

Our means of accomplishing the foregoing objects may be more readily understood by having reference to the accompanying drawings, which are hereunto annexed and are a part of this specification, in which—

Fig. 1 is a top plan view of a press equipped with our improvement;

Fig. 2 is a vertical sectional view taken in front of the attachment;

Fig. 3 is an end elevation;

Fig. 4 is a section taken on the line 4—4 in Fig. 2 in the direction indicated by the arrows;

Fig. 5 is a fragmentary plan view of the attachment;

Fig. 6 is a section taken on the line 6—6 in Fig. 2 in the direction indicated by the arrows;

Fig. 7 is a detailed view showing the method of carrying the current to the heating element;

Fig. 8 is an end view of the same;

Fig. 9 is a side view; and

Fig. 10 is a diagrammatic view showing the

rollers in their relation to each other and to the type bed.

Similar reference numerals refer to similar parts throughout the entire description.

As shown in the drawings the press is of the type known as a Kelly press. This press has a reciprocating type bed 1 carried on rollers 2, only a portion of which are shown since the construction of the press constitutes no part of our invention. A rack 3 is carried by the type bed 2.

Our attachment is mounted in multiple bearing plates 5 which are secured to the frame of the press by screws 6 or in any other desired manner. Only one of these plates is shown as they are duplicates except that they are right and left. The plates 5 provide bearings for the ends of the rollers forming the attachment, and also support a shaft 4 which connects the bearing plates.

Idler gears which are used to convey motion from the rack to the gears secured to the shafts of the various rollers, are mounted on stub shafts carried by one of the plates 5.

A form roller 7, preferably made of rubber secures the melted wax carbon from the ink plate located sufficiently rearward to pass under the form roller 8 located near the center of the press which applies the wax carbon to the type or printing plate 9.

Obviously when the type bed is in the extreme rearward position with the front portion remaining under the impression cylinder, as is customary, the type or printing plate must not be located at a point beyond this inking form roller 8 or it will not receive any ink.

It will be clear from this description that if a printing plate 9 is located adjacent the front 10 of the type bed 1 that it would not be available for printing since it would not receive any ink. When the type bed passes to the rear the printing plate 40 9' passes under the inking form roller 8 which deposits the melted wax carbon thereon. As the type bed moves forward the plate is carried under the impression cylinder and the wax carbon spot is transferred to the sheet of paper (not shown). 45 There is always a quantity of wax carbon remaining on the plate after it has made an impression. As a consequence, when this plate passes under the form roller 7 it transfers to that roller whatever melted wax carbon remains on the plate. 50 Inasmuch, however, as these plates 9 and 9' are located at different positions on the type bed in order to print spots of wax carbon on the paper it is quite apparent that, regardless of the amount of wax carbon which might be deposited upon the 55

form roller 7 in registry with the printing plate 9', it would not have any effect whatever as far as inking plate 9 is concerned. Moreover, by this time the wax carbon has hardened by reason of its being below the critical temperature at which it can be worked so that it could not be spread by the vibrator roller. I, therefore, provide means for heating the vibrator roller. This melts the wax carbon to a consistency at which it will flow. The 10 vibrator roller 11 is contacted by a rider roller 12 which is preferably formed of rubber and this rider roller operates to spread the melted wax carbon picked up from the plate 9' by the form roller 7 over the surface of the vibrator roller, which, in turn, retransfers it to the form roller 7 so that the melted wax carbon will be on the roller 7 so that it will register with the plate 9 and thereby ink it so that when it passes underneath the impression roller and contacts the paper (not shown) it 20 will transfer to the paper the wax carbon thereon.

In this way we make it possible to locate the printing plates at any point on the type bed and yet deliver to them melted wax carbon at the critical temperature requisite to produce good work. The rollers are positively driven in the following manner. Idler gears 16 and 17, the teeth of which mesh with each other, are mounted on stub shafts 18 and 19 which are secured in one of the bearing plates 5.

30 The teeth of the intermediate or lower idler 16 are in mesh with the teeth of a driven gear 20 which meshes with the teeth of the rack and converts the reciprocating motion of the rack to rotary motion which is transferred to the idlers 16 and 17. The teeth of idler 17 is in mesh with a driven gear 21 which is mounted on the shaft 21' of the vibrator roller 11. The teeth of gear 21 mesh with gear 30 fixedly mounted on the shaft 31 of the rider roller 12.

40 This shaft 21' extends beyond the bearing plate 5 and carries a gear 22 which meshes with a gear 23 secured to the shaft 23' of the form roller 7 thus providing a positive drive for all of the rollers in the attachment.

45 Adjustment of the contact of the form roller 7 with the printing plate or plates is similar to that used on standard equipment, i. e., adjusting screws 25. The contact of the rider roller with the vibrator roller is adjusted by swinging the arms 50 26 on rod 4 and clamping it with set screws 28. Obviously these adjustments are duplicated at the other side of the press (not shown). The metal vibrator roller 11 contains an electric heating element 29 one terminal 30 of which is attached to a 55 collector 31 and the other to a collector ring 32. The rings are insulated from each other and are rigidly attached to the end of the vibrator roller 11. The carbon brushes which contact the collector rings 31 and 32 are contained in a housing 60 34 mounted in a block 35 formed of insulating material which may be attached to the bearing plate 5 as shown in Figs. 7, 8 and 9 or in any desired manner.

Having described our invention what we regard 65 as new and desire to secure by Letters Patent is—

1. In a printing press for printing wax carbon spots on sheets of paper having a frame, an impression cylinder, a form roller on one side of said cylinder, a reciprocating type bed having plates 70 thereon one of which is adjacent the front edge of said type bed and in advance of said form roller when said bed begins its printing stroke, and a rack on said bed; bearing plates secured to the frame on the other side of the impression cylinder, shafts journaled in said bearing plates, a second

form roller on one of said shafts adapted to contact both of said plates, a metal vibrator roller on another shaft, said vibrator roller being in contact with said second form roller, a rider roller on another of said shafts which contacts said 5 vibrator roller only, gears actuated by said rack to rotate said vibrator, rider and second form rollers, and means to heat said vibrator roller.

2. In a printing press for printing wax carbon spots on sheets of paper having a frame, an impression cylinder, a form roller on one side of said cylinder, a reciprocating type bed having plates thereon one of which is adjacent the front edge of said type bed and in advance of said form roller when said bed begins its printing stroke, and a 15 rack on said bed; bearing plates secured to the frame on the other side of the impression cylinder, shafts journaled in said bearing plates, a second form roller on one of said shafts adapted to contact both of said plates, a metal vibrator 20 roller on another shaft, said vibrator roller being in contact with said second form roller, a rider roller on another of said shafts which contacts said vibrator roller only, and a train of gears actuated primarily by said rack to positively rotate 25 said vibrator, rider and second form rollers.

3. In a printing press for printing wax carbon spots on sheets of paper having a frame, an impression cylinder, a form roller on one side of said cylinder, a reciprocating type bed having 30 plates thereon one of which is adjacent the front edge of said type bed and in advance of said form roller when said bed begins its printing stroke, and a rack on said bed; bearing plates secured to the frame on the other side of the 35 impression cylinder, shafts journaled in said bearing plates, a second form roller on one of said shafts adapted to contact both of said plates, a metal vibrator roller on another shaft, said vibrator roller being in contact with said 40 second form roller, a rider roller on another of said shafts which contacts said vibrator roller only, a driven gear in mesh with said rack, an idler gear in mesh with said driven gear, a second idler gear, a driven gear in mesh with 45 the second idler, fixedly mounted on the shaft of the vibrator roller, a gear in mesh with the gear on the vibrator roller shaft fixedly mounted on the shaft of said rider roller, the shaft of the vibrator roller and second form roller extending beyond one of said bearing plates, a second gear on the vibrator roller shaft, and a gear on the shaft of the second form roller in mesh therewith.

4. In a printing press for printing wax carbon spots on sheets of paper having a frame, an impression cylinder, a form roller on one side of said cylinder, a reciprocating type bed having plates thereon one of which is adjacent the front edge of said type bed and in advance of said form roller when said bed begins its printing stroke, and a rack on said bed; bearing plates secured to the frame on the other side of the impression cylinder, shafts journaled in said bearing plates, a second form roller on one of said shafts adapted to contact both of said plates, a metal vibrator roller on another shaft, said vibrator roller being in contact with said second form roller, a rider roller on another of said shafts, which contacts said vibrator roller only, a driven gear in mesh with said rack, an idler gear in mesh with said driven gear, a second idler gear, a driven gear in mesh with the second idler, fixedly mounted on the shaft of the vibrator roller, a gear in mesh with the gear on the 70 75 80 85 90 95 100

5. vibrator roller shaft fixedly mounted on the shaft of said rider roller, the shaft of the vibrator roller and second form roller extending beyond one of said bearing plates, a second gear on the 5 vibrator roller shaft, a gear on the shaft of the second form roller in mesh therewith, and means to heat said vibrator roller.

5. In a printing press for printing wax carbon spots on sheets of paper having a frame, an 10 impression cylinder, a form roller on one side of said cylinder, a reciprocating type bed having plates thereon one of which is adjacent the front edge of said type bed and in advance of said form roller when said bed begins its print- 15 ing stroke, and a rack on said bed; bearing plates secured to the frame on the other side of the impression cylinder, shafts journalled in said plates, a second form roller on one of said shafts adapted to contact both of said plates, a metal vibrator 20 roller on another shaft, said vibrator roller being in contact with said second form roller, a rider roller on another of said shafts which contacts said vibrator roller only, an electric heating element in said vibrator roller, collector rings se-

cured to terminals of said heating elements, and brushes adapted to contact said collector rings.

6. In a printing press for printing wax carbon spots on sheets of paper having a frame, an impression cylinder, a form roller on one side of 5 said cylinder, a reciprocating type bed having plates thereon one of which is adjacent the front edge of said type bed and in advance of said form roller when said bed begins its printing stroke, and a rack on said bed; bearing plates 10 secured to the frame on the other side of the impression cylinder, shafts journalled in said bearing plates, a second form roller on one of said shafts adapted to contact both of said plates, a metal vibrator roller on another shaft, 15 said vibrator roller being in contact with said second form roller, a rider roller on another of said shafts which contacts said vibrator roller only, means to heat said vibrator roller, and a train of gears actuated primarily by said rack to posi- 20 tively rotate said vibrator, rider and second form rollers.

GEORGE A. RUTKOSKIE.
NELSON S. WELK.
